UNITED STATES PATENT OFFICE

ALBERT L. HOWARD, OF BROCKTON, MASSACHUSETTS, ASSIGNOR TO HAMILTON-WADE COMPANY, OF BROCKTON, MASSACHUSETTS, A CORPORATION OF MASSACHUSETTS

ORNAMENTAL PRODUCT AND METHOD OF PRODUCING THE SAME

Application filed June 16, 1930. Serial No. 461,510.

This invention relates to composite ornamental products of sheet material and includes within its scope a novel method of producing the same.

5 While the field of the invention extends to substantially every art wherein an ornamental surface may be desired, it is herein shown for purposes of illustration in its application to the manufacture of shoes and under such circumstances the materials used

10 will be upper leather and textile fabric. Various expedients have been attempted in the past for producing an ornamental effect by inlaying work in contrasting colors or by 15 various methods of weaving or lacing together upper leather of dissimilar character.

While my invention relates to this general field of endeavor, I have discovered a new manner of associating layers of sheet material and of securing them together whereby 20 a novel ornamental effect of striking artistic merit may be secured and which at the same time may be produced by a process which may be carried out economically under the 25 usual conditions of commercial manufacture.

The product of my invention, moreover, affords an opportunity for designs of widely differing appearance and I am thus enabled to meet the diverse tastes of different con-

30 sumers by varying one or more of the constituent portions of my product in character, proportion or color.

In one aspect, my invention comprises a composite ornamental product comprising 35 dissimilar layers of sheet material each having a series of spaced slots therein and being superimposed with portions of the lower layer or layers filling the slots of the uppermost layer and secured in position therein.

40 As applied to the shoemaking art, for example, I may provide in the vamp a series of slots and then place beneath the line of slots an underlying layer similarly slotted but disposed with its slots in line with the

45 spaces of the vamp. By causing the material of the underlying layer to enter and fill the slots in the vamp, I have produced in the surface of the vamp a line of ornamental inserts which may be of a color contrasting 50 with the vamp or of a material otherwise

presenting an appearance different from the surface of the vamp. As the shape of the inserts is determined by the shape of the slots in the vamp, I am enabled to secure a further ornamental effect by forming the 55 slots in the vamp of an ornamental outline. It will be apparent also that by using an underlying strip of variegated color a similar appearance may be given to the inserts appearing on the surface of the vamp.

The facing layer and underlying layer 60 may be secured together in any desired manner. Additional valuable characteristics may be attained by employing a filamentous member for this purpose, such as a lacing 65 of upper leather or textile material, and in lacing the two layers together in the manner explained. When this is done, the lacing member is exposed between the portions of inlay so that a three-colored effect is pre- 70 sented and this effect may be heightened by employing a ribbon or silk or other textile material. The lacing or filamentous member may be woven under the portions of the underlying layer and over the portions of the 75 facing layer, deflecting the material of each slightly at the edge of each ply and lying itself substantially flat upon the surface of the facing layer.

As already intimated, the product above 80 described may be produced by methods well adapted for commercial manufacture; for example, the facing and underlying layers may be easily and rapidly perforated by perforating machines available upon the market, 85 then superposed with their respective perforations in staggered relation, and finally the product is completed and the layers maintained permanently in the relation thus established by weaving the lacing member in 90 and out of the slots in the manner already explained.

The product of my invention and the method of producing the same will be best understood and appreciated from the following description of certain preferred embodiments thereof, selected for purposes of illustration and shown in the accompanying drawing, in 95 which

Fig. 1 is a plan view of an ornamental vamp with a portion broken away;

Fig. 2 is a fragmentary view of a product having ornamental slots in its facing layer;

Fig. 3 is a plan view of a strip product of the general character of the vamp shown in Fig. 1;

Fig. 4 is a fragmentary view in perspective, on an enlarged scale, of a portion of the vamp shown in Fig. 1;

Fig. 5 is a longitudinal sectional view, on an enlarged scale, taken on line V—V of Fig. 1; and

Fig. 6 is a view in perspective of a strip product made with a cord.

As already stated, my invention may be embodied in practically any composite product which may be made of flexible sheet material. Thin upper leather used in the manufacture of boots and shoes lends itself particularly well to ornamentation by the method of my invention. Accordingly, in Fig. 1 I have shown a vamp 10 intended for a shoe upper and provided with three lines of ornamentation in its forepart. In producing this ornamentation, the vamp is first perforated with a line of uniformly spaced perforations 12. As herein shown, these are arranged transversely of the line of ornamentation and have curved or rounded ends, although the outline of the perforations will depend upon the effect which it is desired to secure in the ornamentation. The vamp 10 constitutes the exposed or facing layer 30 of the product being described.

The underlying layer in the product shown in Fig. 1 constitutes a thin strip of ribbon 14 of a dark-colored upper leather and this, as shown through the broken away part of the vamp, is also perforated, having a row of apertures 16 similar in shape and spacing to the apertures 12 of the vamp. The width of the underlying strip 14 is immaterial so long as it exceeds that of the apertures 12 of the vamp, and the apertures 16 may be of any desired shape or may be reduced in width to mere slits since it is the material of the spaces 18 only which is exposed in the finished product.

The vamp 10 constituting the facing layer and the strip 14 constituting the underlying layer are then assembled with their respective apertures out of line or in staggered relation. This brings the material of the spaces 18 of the underlying strip into registration with the apertures 12 of the vamp 10. The material of the spaces 18 of the underlying strip is then forced upwardly into the apertures 12 of the vamp, completely filling the apertures and bulging somewhat above the surface of the vamp, as shown more clearly in Fig. 4. This relationship is made permanent by threading or weaving a filamentous member alternately over the surface of the vamp 10, then

under a space 18 of the underlying strip 14, then over the surface of the vamp, and so on. As shown in Fig. 1, I have employed a ribbon 20 of upper leather of substantially the same color and texture as the material of the vamp 10 as a lacing member. This may be readily threaded or run-in in the manner explained with the assistance of a needle or bodkin and is then drawn so that it lies substantially flat upon the surface of the vamp. The position of the ribbon 20 and the manner in which it holds the layers of material in place will be apparent from the sectional view of Fig. 5. It will be understood that the ribbon 20 holds the material of each space 18 of the underlying strip in a position completely to fill the apertures 12 of the vamp, thus forming in each perforation a small insert having somewhat the effect of an inlay, the outline whereof being determined by the outline of the apertures 12. In Fig. 1 the lines of ornamentation are shown as terminating in raw or unfinished ends but it will be understood that in incorporating such a vamp into a shoe the ends of the ornamental lines will be finished either by being lasted under, overlapped or folded.

In Fig. 2, I have illustrated a modification of my invention in which the filamentous member is omitted and the two layers secured together by cement. In this case the facing layer 30 is provided with a row of heart-shaped apertures 32. The underlying layer 34 comprises a ribbon of thin upper leather of a darker color than the facing layer and this is provided with a series of slots 36 equally spaced and separated by a distance slightly exceeding the width of the heart-shaped apertures of the facing layer. The facing layer 30 and the underlying ribbon 34 are superimposed with the spaces of the ribbon 34, registering with the apertures 32 of the facing layer. The two layers are then forced into intimate contact so that the material of the underlying ribbon 34 bulges somewhat through the apertures 32, thus producing in each aperture a heart-shaped insert 36'. It will be apparent that the slots 36 render the ribbon 34 relatively flexible whereby to permit the bulging of its material into the apertures 32 and eliminate to a great degree the possibility of the strip 34 pulling away and becoming detached from the layer 30. It will be apparent that the outline of the apertures 32 in the facing layer may be varied to suit the taste of the manufacturer and that a ribbon slotted as shown in Fig. 2 may be employed in the production of designs having many characteristic differences.

In Fig. 3 I have shown my invention as embodied in a three-color strip product which may be used as an ornamental binding or strap. In this case, the facing layer comprises a narrow ribbon 40 of a light-colored upper leather provided with perforations

similar in shape to those of the vamp shown in Fig. 1 but somewhat smaller. The underlying layer comprises a slightly wider ribbon 42 of a darker upper leather and this is similarly provided with a row of apertures

5 44. The two ribbons are superimposed with their respective apertures in staggered relation and then a lacing member, comprising a colored ribbon 50 of textile material, is threaded through the apertures, passing over 10 the surface of the facing ribbon 40 and under the spaces between the apertures 44 of the underlying ribbon 42. The composite ornamental strip produced, therefore, presents a 15 light-colored facing 40 flanked at either edge by a narrow dark-colored border and embellished with a series of dark inlays or inserts 46 alternating with a series of sections of brilliant color supplied by the ribbon 50.

20 In Fig. 6 I have shown a further modification of my invention, in which I employ as a filamentous member a cord of substantially circular cross section as distinguished from the flat ribbons shown in Figs. 1 and 3. In this case, the facing layer comprises a ribbon 60 of a dark-colored upper leather provided with a series of substantially square apertures or perforations. The underlying layer comprises a narrower ribbon 62 of a 25 light-colored upper leather similarly perforated and disposed with its perforations in staggered relation to those of the facing ribbon 60. The material of the spaces in the underlying ribbon 62 is maintained in the apertures of the ribbon 60 by a round cord of 30 brightly-colored rayon or the like which is laced alternately over the surface of the facing ribbon 60 and under the material of the spaces in the underlying ribbon 62. The underlying ribbon 62 in this case is hidden except at the center of the strip, where it is 35 brought through the apertures of the ribbon 60. The composite product thus produced is a three-color effect but without the border 40 shown in Fig. 3.

45 It will be apparent that the product illustrated in Figs. 1, 3 and 6 is reversible in character and that the design shown on one face of the product is substantially duplicated on the other if the material used is of the same color on both sides, or different colors if the opposite sides of the material are 50 differently finished. This characteristic of the product of my invention is of substantial 55 value from the commercial standpoint as it enables the manufacturer to keep in stock practically two different designs for each item of his inventory.

60 In the foregoing description I have referred to a line or row of apertures in the layers of the composite product. This line or row may be straight, as shown in the illustrated examples of the invention, or may be curved as, for example, in the form of a scroll 65 if more suitably applied in such form to work

of curved outline or if a curved form of ornamentation is desired.

Having thus described my invention, what I claim as new and desire to secure by Letters Patent is:

70 1. A composite ornamental product comprising dissimilar layers of flexible sheet material superimposed one on the other, the uppermost layer having a line of apertures of decorative outline and the underlying layer being slotted in locations opposite to the spaces between the apertures of the uppermost layer and having intermediate portions in contact with and outlined by the apertures of the uppermost layer, and means holding 75 the underlying layer in immovable face to face contact with the portions of the uppermost layer bordering its said apertures.

80 2. A composite ornamental strip for use in shoemaking, comprising an underlying ribbon having a series of slots therein, a superimposed ribbon having openings cut therein which are disposed in staggered relation to the slots of the underlying ribbon, and tape of textile material threaded through the two 85 ribbons in such manner as to hold portions of the underlying ribbon in the openings of the superimposed ribbon, the proportions and arrangement being such that the openings in the superposed ribbon are hidden beneath the 90 said portions and tapes.

95 3. An ornamental binding comprising a facing strip having a series of equally-spaced transversely-elongated apertures arranged 100 symmetrically between its edges, a backing strip cut out to form spaced cross bars which register with the apertures of the facing strip, said strips being superimposed with the cross bars of the backing strip extending into and completely filling the apertures of the facing 105 strip, and a lace member of substantially the same width as said apertures engaging said cross bars and overlying portions of the facing strip between said apertures.

110 4. The method of producing a composite ornamental article, which consists in forming a row of perforations in a facing layer of sheet material, similarly perforating an underlying layer, superimposing the two layers with their respective perforations in 115 staggered relation, completely filling the perforations of the facing layer with the material of the underlying layer and immovably securing the layers in such relation.

120 5. The method of producing a composite ornamental article, which consists in forming a row of perforations in a facing layer, similarly perforating an underlying layer, superimposing the two layers with their respective perforations out of line with each other, and then lacing a filamentous member of a width substantially equal to the width 125 of the perforations under portions of the underlying layer and over portions of the facing layer thereby maintaining the two in 130

fixed relation and closing the first-named perforations by said member and the first-named portions.

6. A composite ornamental product comprising two layers of flexible sheet material one having a line of relatively spaced apertures and the other having a line of relatively spaced apertures in alignment with the first line but arranged alternately thereto, the two layers being cemented together in face to face contact with the material of the underlying layer between its apertures bulging into the first-named apertures throughout their entire areas.

15. 7. A composite ornamental product comprising two layers of flexible sheet material one having a line of relatively spaced apertures and the other having a line of relatively spaced apertures in alignment with the first line but arranged alternately thereto, and filamentous means securing the two layers together with the material of the underlying layer between its apertures engaged within the first-named apertures throughout their entire areas.

30. 8. A composite ornamental product comprising two layers of flexible sheet material one having a line of relatively spaced apertures and the other having a line of relatively spaced apertures in alignment with the first line but arranged alternately thereto, and a strip lacing passing through the apertures of the underlying layer and over the outer face of the outer layer and securing the 35 layers together with the material of the underlying layer between its apertures engaged within the first-named apertures throughout their entire areas.

40. 9. A composite ornamental product comprising two layers of flexible sheet material one having a line of relatively spaced apertures and the other having a line of relatively spaced apertures in alignment with the first line but arranged alternately thereto, and a strip in alignment with the said apertures and resting on the outer face of the upper layer and engaging beneath the material between the apertures of the underlying layer in a manner binding the two layers 45 together, the strip being of a width substantially equal to the width of the apertures.

ALBERT L. HOWARD.
